Charles H. Ohly,

Russell M. Everett,
ATTORNEY.

UNITED STATES PATENT OFFICE.

CHARLES H. OHLY, OF SUMMIT, NEW JERSEY.

NECKTIE-HOLDER.

1,016,357.

Specification of Letters Patent.

Patented Feb. 6, 1912.

Application filed March 27, 1911. Serial No. 617,013.

To all whom it may concern:

Be it known that I, CHARLES H. OHLY, a citizen of the United States, residing at Summit, in the county of Union and State 5 of New Jersey, have invented certain Improvements in Necktie-Holders, of which the following is a specification.

This invention relates to that class of necktie holders represented by the one 10 shown in my prior application Serial No. 580,818, filed September 7, 1910, and which serve to hold a necktie in place upon a wearer without it extending clear around the wearer's neck.

15 The objects of the present improvements are to provide a wire holder having means for engaging a collar-button which can be varied in height to accommodate either high or low collars; to enable such adjustment to take place automatically, and to this 20 end to form the lower ends of the lateral loops of the holder in a resilient extension; to secure the ends of the wire forming such extension loosely around the attaching 25 means, so that they can turn thereon; to provide a compressible holder upon which either a small knot or a large one can be tied; to provide means for concealing the 30 lateral loops even though only a very small knot is tied, and to obtain other advantages and results as may be brought out in the following description.

Referring to the accompanying drawings, in which like numerals of reference indicate 35 the same parts throughout the several figures, Figure 1 is a front view of my improved holder as it appears when worn with a high collar, the collar being shown in dotted lines, and no tie shown, for greater 40 clearness; Fig. 2 is a similar view of the holder as it appears when worn with a low collar, showing the compression which occurs, and also showing the front extension upon which the tie is knotted as stretched 45 or extended laterally so that the necktie will form a larger knot; Fig. 3 is an end or side view of the necktie holder; Fig. 4 is a section upon line A—A of Fig. 1, looking in the direction indicated by the arrow, and 50 Fig. 5 is a section taken on line B—B of Fig. 4, looking in the direction indicated by the arrow.

In said drawings, 1 indicates a wire frame 55 constituting the body portion of my improved holder, said body portion having lateral loops 2, 2 adapted to project under

the wings of a collar, a front downward extension 3 around which a necktie is to be knotted, and a rear downwardly extending attaching and supporting portion. As 60 shown, the said front extension 3 comprises a closed loop around which the necktie is to be knotted or tied, said extension being normally large enough to make a good sized knot, but being flexible so that it can be 65 squeezed into a narrower shape, as shown in Fig. 1, to enable a very small tight knot 70 to be tied upon it if desired. The wearer changes the shape of this closed loop 3 with his fingers, according to the size of the 75 knot in which he wishes to arrange his necktie. At the top of the said loop or front extension 3 the wire is twisted together, as at 80 4, and from thence the strands diverge laterally and somewhat rearwardly and are returned to form the lateral loops 2, 2. The 85 returned portions of the wire lie below the said upper arms 5, 5 of the loops and from the inner ends of the lower arms 6, 6 the ends of the wire curve gently downward, 90 as at 7, 7, and crossing each other are curled beneath and around the neck of an attaching socket-piece 8. This secures the said attaching socket-piece to the rear downward extension of the holder formed by the downwardly curved portion 7, 7, but the said 95 ends 9 of the wire are not wrapped so tightly upon the neck of the socket-piece, but that they can slip or turn thereon. It will be noted that said portions 7, 7 have their 100 convexities inward, or each toward the opposite loop, and that after crossing each other each arm extends downward around the socket-piece at the opposite side thereof from the loop to which the arm is attached. 105 This insures that the arms are of maximum length and resiliency, and that when pressed downward the curved portions simply bend still more, and thus increase their resiliency or resistance to bending. Normally the said 110 rear extension formed by the downwardly curved portions 7, 7 stretches out to its full length, somewhat as shown in Fig. 1, but the holder is always ready to accommodate itself to a low collar by compression of the said rear extension, as shown in Fig. 2. Here the downwardly curved portions 7, 7 are bent upward carrying the lower arms 6, 6 with them, so as to shorten the rear downward extension carrying the socket-piece 8, materially, and in doing this the ends 9 of the wire wrapped around the said

socket-piece have turned pivotally thereon to a greater or less extent. The said socket-piece 8 provides a rearwardly opening chamber to frictionally receive the head of a collar button, not shown, after the manner of a glove fastener. Said socket-piece is shown as comprising a front cap 10 and a slotted neck 11 having at its end an outer peripheral flange 12 which is opposed to the cap 10 and serves to clamp the ends 9, 9 of the wire therebetween.

Preferably a shield 13 is perforated to receive the neck 11 and is mounted thereupon with the wire ends 9, 9, said shield lying in front of said wire ends, or between them and the cap 10 of the socket piece. This shield 13 extends upward and laterally toward both sides so as to lie in front of the curved portion 7, 7 of the wire 20 and to extend somewhat along the lower arms 6, 6 of the lateral loops 2, 2. Said shield not only protects the knot of the tie from rubbing against the said wire parts, but furthermore the shield is made of white 25 celluloid or other suitable material so that it overlies any portions of the wire arms 6, 6 which might otherwise show with a very low collar cut wide open in the front between the knot and the edges of the wings 30 of the collar. With the shield, any such spaces are bridged or covered, as clearly shown in the drawings, and a neat and 35 pleasing appearance is obtained.

Having thus described the invention, what I claim is:

1. A necktie holder comprising a rearwardly opening socket-piece adapted to receive the ball-head of a collar button, said socket-piece having front and rear laterally projecting portions and an intermediate neck, and a wire frame having lateral loops adapted to project under the wings of a collar and front and rear downward extensions, the front extension constituting a flexible form for knotting a tie upon and the rear extension comprising resilient arms

constituting continuations of the lower sides of the lateral loops curved downward across each other each to the opposite side of the neck of the socket-piece from its loop and 50 curled around said neck, the convexity of each arm being toward the opposite loop and said arms being free from each other so as to bend from said socket-piece each independent of the other, said laterally projecting portions of the socket-piece holding the arms so curled around the neck of the socket-piece between themselves, whereby said arms are connected to each other, the socket-piece is connected to the wire frame 60 and an attaching means provided.

2. A necktie holder comprising a wire frame having lateral loops adapted to project under the wings of a collar and front and rear downward extensions, the front 65 extension constituting a tie form and the rear extension being formed of the ends of the wire and providing attaching means, and a shield mounted upon the front side of said rear extension and projecting over 70 the said extension to lie between it and the front extension.

3. A necktie holder comprising a rearwardly opening socket piece having a neck, a wire frame having lateral loops adapted 75 to project under the wings of a collar and front and rear downward extensions, the front extension constituting a form for knotting a tie and the rear extension comprising resilient arms bent downward from 80 the lower sides of the lateral loops and curled around the neck of said socket-piece, and a shield apertured to receive said neck of the socket-piece and lying between the head of the socket piece and said arms, said 85 shield projecting over the said arms and adapted to cover the entire portions thereof which are exposed by the collar.

CHARLES H. OHLY.

In the presence of—

CORNELIUS ZABRISKIE,
FRANCES E. BLODGETT.
